On The Wight. Isle of Wight Distillery scales up with new Mermaid Gin bottle. Mar. 5, 2019. <https://onthewight.com/isle-of-wight-distillery-scales-up-with-new-mermaid-gin-bottle/> (Year: 2019).*

Primary Examiner — Darcey E Gottschalk(74) *Attorney, Agent, or Firm* — The Concept Law Group, PA; Scott D. Smiley; Scott M. Garrett

(57)

CLAIM

The ornamental design for a bottle, as shown and described.

DESCRIPTION

FIG. 1 is a front perspective view of a bottle;

FIG. 2 is a front view thereof;

FIG. 3 is a rear view thereof;

FIG. 4 is a left side view thereof;

FIG. 5 is a right side view thereof;

FIG. 6 is bottom view thereof; and,

FIG. 7 is a top view thereof.

The broken line around the outline of the bottle and the front and rear label areas depicts environment only and form no part of the claimed design.

1 Claim, 7 Drawing Sheets(56)
